UNITED STATES PATENT OFFICE.

CHARLES G. BURKE AND EDWARD J. BURKE, OF BROOKLYN, NEW YORK,
ASSIGNORS OF ONE-HALF TO JOHN Q. A. WHITTEMORE, OF BOSTON,
MASSACHUSETTS.

TELEPHONE SYSTEM.

No. 846,894.

Specification of Letters Patent.

Patented March 5, 1907.

Application filed October 14, 1905. Serial No. 282,732.

To all whom it may concern:

Be it known that we, CHARLES G. BURKE and EDWARD J. BURKE, citizens of the United States, and residents of the borough 5 of Brooklyn, county of Kings, State of New York, have invented new and useful Improvements in Telephone Systems, of which the following is a specification.

Our invention relates to telephone systems; and it has for its object to provide an annunciator which will operate to indicate to a central operator that a subscriber has called and which will also operate to indicate when the subscriber has completed the 10 conversation.

It has for its further object to provide an annunciator which, in addition to the functions stated above, will indicate in a different manner when the subscriber has completed 15 his conversation from that when the subscriber first calls the central station.

It has for its further object to provide an annunciator which will indicate in one manner when the subscriber desires a connection, 20 and again in a different manner when one of the connected subscribers desires to be disconnected or hangs up his receiver, and again in a different manner when the other subscriber desires to be disconnected, and again in a different 25 manner when both subscribers have hung up their receivers.

A further object of the invention is to provide a means for signaling the operator at the beginning and at the end of the conversation which will be located in proximity to the subscriber's jack. Heretofore it has been customary to provide a set of subscribers' 30 signaling instruments and another set of signaling instruments for the plug-circuits. These two sets of instruments in systems now known in the art are located at different places in the operators' tables, so that the operators have two sets of instruments to 35 watch.

In making connections between subscribers in the systems now known in the art the plugs are inserted in jacks connected to the subscriber's station. The jacks are located in 40 all parts of the operator's board. The signaling means for the plugs are located over the plug-seats, so that when a conversation is completed the plug lines or wires have to be traced from the plug-seats through other plug lines or wires which are being

used for connecting other subscribers to the 55 particular pair of plugs which are connected to the subscribers that have completed their conversation. This complexity increases when the subscribers are connected to multiple boards. By our invention the operator 60 is required to watch only the lamps which are associated with the jacks of the subscribers directly under the supervision of the operator.

In our invention the annunciators perform 65 the double function of indicating when the subscriber desires a connection to be made and when the conversation is completed and are located in the vicinity of the jacks. There is consequently but one set of annunciators for the operator to watch. In our invention we use small electric lamps for 70 signaling the operator. Each lamp pertaining to each subscriber's circuit may be placed in proximity to each subscriber's jack. When 75 a subscriber desires a connection to be made and when he has completed his conversation, the lamp of his circuit which is located in the vicinity of the jack will light up and indicate to the operator to insert or withdraw her 80 plug from that particular jack. Likewise the lamp of the other subscriber who has connected with the first subscriber will light up, and the operator will pull out the connecting plug from the jack of that subscriber. This 85 prevents mistakes in withdrawing plugs, reduces the number of annunciators, and reduces the area to be watched by the operator, and consequently greatly increases the 90 capacity of the central station.

The invention also consists in features set forth in the claims and which are disclosed in the following description and shown in the drawings.

In the drawing, Figure 1 illustrates diagrammatically the system embodying our invention. Fig. 2 illustrates the application of our invention to multiple-board central systems; and Fig. 3 illustrates a plug used in connection with the system illustrated in 100 Fig. 2.

Referring to the drawings, 1 and 8 indicate receiver-hooks located at two of the subscribers' stations.

2 and 9 indicate receiver-hooks.

6 and 13 indicate upper contacts, which are closed when the receivers are removed from the hooks in the manner well known in the art.

- 5 and 12 indicate transmitters.
 4 and 11 indicate condensers, and 3 and 10 indicate bells.
 15 and 16 indicate the line connections between one subscriber's station and the central station, and 14 and 17 indicate line connections between the other subscriber's station and the central station.
 36 and 46 indicate jack-sleeves.
 10 35 and 47 indicate spring-contacts located in the jack. They have insulated tips.
 37 and 45 indicate plugs adapted to be inserted in the jacks and make contact with the rings and springs thereof in the manner well known in the art.
 15 38 and 39 indicate wires connecting the plugs.
 62 is a generator for producing a signaling-current.
 20 44 is a ringing and listening key.
 42 is a listening-telephone.
 The subscribers' stations are connected to the battery 18, located at the central station. In one of the lines leading to each of the subscribers' stations is connected a relay-magnet. These are marked in the drawing 19 and 20. When the receiver is removed from the hook, a current from the battery 18 passes through the lines and the relay-magnet and causes it to operate.
 30 The magnet 19 is provided with armatures 51 and 52. Likewise magnet 20 is provided with armatures 53 and 54. Armatures 51 and 52 make contact normally with contacts 21 and 25 and when energized make contact with contact 55 and 26. Armatures 53 and 54 normally make contact with contacts 22 and 24, and when the magnet 20 is energized they make contact with contact 23 and 56.
 40 A circuit-breaker 43 for producing a pulsating current is provided for signaling the operator when connection is desired. The circuit-breaker consists of a segmental wheel 31, which is adapted to make and break connection with contact 30 as the wheel rotates. The battery 32 is connected with all the spring-contacts of the system which corresponds with contacts 35 and 47 through the lamps 50 51, while contact 30 is connected 50 to all of the contacts which correspond to contacts 26 and 23. A battery 32 is also connected to the segmental wheel 31. In the normal operation of the system the wheel 31 is constantly rotating.
 55 When the subscriber lifts the receiver 8, he closes a contact 13. A current is then allowed to flow from the battery 18 through the transmitter 12, contact 13, and magnet 20. This energizes magnet 20 and causes its 60 armatures to close contact with contacts 23 and 56. A vibrating current then flows from the battery 32 through the wheel 31, contact 30, 23, 56, 47, and lamp 51. This causes the lamp 51 to flash, which indicates to the operator that a connection is desired by a subscriber. The operator inserts the plug 45 in the jack which is in the vicinity of the flashing light 51 and at the same time throws the key 44 to the right. A circuit for voice-currents is thus closed from the battery 18, 70 through the receiver 42 and coil 57, contacts 58 59, plug 45, sleeve 60, transmitter 12, receiver 8, to the battery 18, and it also breaks the circuit passing from battery 32 through the lamp 51 and contact 47. The 75 flashing of the lamp 51 ceases, and the operator inquires of the subscriber what number is wanted. When the number is ascertained, the operator inserts the plug 37 in the jack associated with the number given. In this 80 particular case it is inserted in the jack 36, and at the same time the key 44 is thrown to the left. Contact 35 is separated from the contact 61. At the same time it closes a circuit from the generator 62, contacts 63 85 and 64, plug 37, sleeve 36, bell 3, condenser 4. After the cessation of the ringing-current and before the response of the called subscriber the lamp 50 glows steadily. The subscriber then lifts the receiver 1, and the 90 circuit is closed from the battery 18 to the receiver 1, transmitter 5, plug 37, key 44, plug 45, transmitter 12, receiver 8, back to the battery. The battery feeds across the circuit through the magnets 19 and 20, 95 which operate as impedance-coils to the sleeves 36 and 46. When the conversation between the subscribers is completed, the subscribers hang up their receivers and the circuits through the receiver-hooks 2 and 9 100 are broken. This causes the magnets 19 and 20 to become deenergized, and the armatures of the magnets spring back in the manner well known in the art. This closes a circuit from the battery 32, through the lamps 50 105 and 51, contacts 35 and 47, 21 and 24, 25 and 22, back to the battery 32. The constant current from the battery 32 causes the lamps 50 and 51 to glow with a steady light, which indicates to the operator that the conversation is completed and who then withdraws the plugs 37 and 45.
 In Fig. 2 is illustrated our invention as applied to multiple-board central systems. The connections of the subscribers' instruments with the central station are the same as those of the system illustrated in Fig. 1 and described above. Each station, however, is connected to a plurality of jacks 36, 46, 70, and 71. Contacts 35 and 47 of the jacks 36 110 and 46 of the system shown in Fig. 2 do not have insulated portions, as in the system shown in Fig. 1. The multiple jacks 70 and 71 are provided with contacts 72 73 74 75. Contacts 72 and 74 are adapted to make contact with the plug, while contacts 73 and 75 have insulations at their ends which prevent connections with the plug, but co-operates with the plug to separate the contact from contacts 76 and 77. Contacts 76 and 77 are 115

connected with the lamps 78 and 79. Contacts 73 and 75 are connected with the battery 32. Contacts 72 and 74 are connected to contacts 21 and 24 of relays 19 and 20 and to one end of the resistances 80 and 81. The other end of the resistances 80 and 81 are connected with contacts 82 and 93 of the jacks 36 and 46. The jacks are connected together by means of the plugs 83 and 84.

10 The plugs used in the system illustrated in Fig. 2 are each provided with a hollow handle 85, on which is mounted a thimble 86. A ball or ring 87 is mounted on the thimble 86 and insulated therefrom by insulation 89. A 15 wire is connected to the thimble 86, and another wire is connected to the sleeve 87. The balls or rings 87 of the plugs are connected in series with the resistance 92. The thimbles 86 are connected with the operator's circuit 20 in the manner well known in the art and are adapted to register with the sleeves of the jacks, which are connected in turn with the subscribers' stations.

When a subscriber desires to converse with 25 any one, he lifts his telephone-receiver 8 from the hook 9. This causes a current to flow from the battery 18, through the relay-magnet 20, receiver-hook 9, transmitter 12, receiver 8, back to the battery 18, as in the case 30 of the system illustrated in Fig. 1. This causes the magnet 20 to become energized and to draw over the armatures 53 and 54, so as to close with the contacts 23 and 56. A current then flows from the battery 32, 35 through the make-and-break device 43, contact 23 56 47, lamp 78, contact 76 73, to the battery 32. This causes the lamp 78 to flash. The operator inserts a plug into the jack 46 and at the same time throws the key 44 over to the right and asks the subscriber 40 what number is wanted. The insertion of the plug into the jack breaks the connection through the lamp 78 and the lamp ceases to flash. The movement of the key 44 connects 45 the operator's talking-circuit with the subscriber's instrument. When the operator ascertains the number wanted, she first touches the end of the thimble 86 to the ring of one of the jacks connected to the subscriber 50 wanted. If the subscriber wanted is busy, the sleeve of the jacks connected thereto will have a certain potential from the battery 18, the fall of the potential between the sleeve and the battery being normally through the high-resistance magnet. 19. Touching the 55 sleeve with the thimble will cause a current to be shunted from the sleeve 71, thimble 86, key 44, and head receiver 42, which will produce a click in the head receiver. If no 60 click occurs, the operator will know that the subscriber wanted is not busy and will insert the plug 85 into the jack 71 and will throw the key 44 to the left. This will cause a current to flow from the generator 62, through 65 the key 44, thimble 86, sleeve 71, bell 3, to the

generator 62. This will cause the bell 3 to ring. A connection will also be established from battery 32, through contacts 25 21, contact 74 87, resistance 92, contact 47, lamp 78, contact 76 73, back to the battery 32. This 70 will cause the lamp 78 to glow somewhat brightly until the subscriber wanted lifts his receiver from the hook in answer to the call of the bell 3. This causes a current to flow through magnet 19 and breaks the connection 75 between contacts 21 and 25. The lamp 78 ceases to glow. The insertion of the plug in the jack 71 and the lifting of the receiver 1 from the hook 2 establishes a connection between the subscribers through the sleeves of 80 the jack and the key 44 on one side and through the connections leading directly to the battery on the other side. The battery 18 is connected in parallel with these connections, as in system shown in Fig. 1. 85

If the subscriber having receiver 1 hangs up his receiver first, magnet 19 will become deenergized and cause the lamp 78, located in the section of the subscriber who first called, to glow somewhat brightly, as described. If, however, the subscriber having receiver 8 hangs up his receiver first, the magnet 20 becomes deenergized and a current is established from the battery 32 through contact 22 and 24, high resistance 81, contact 95 47, lamp 78, contacts 75 73, and battery 32. This will cause the lamp to glow less brightly and will indicate to the operator that the subscriber having receiver 8 has hung up his receiver. When, however, both 90 receivers are hung up, the current from the battery 32 flows in two directions, one through contacts 22 24, resistance 81, contact 47, and the other through contacts 25 21 74, resistance 92, contact 47, and these two paths reduce the resistance by about one-half and cause the lamp 78 to glow very brightly, 100 which will indicate to the operator that both subscribers have hung up their receivers.

If while the operator is trying to call up a subscriber having receiver 1 and the subscriber having receiver 8 desires to communicate with her for any reason, she will merely place receiver 8 on the hook, which will cause the lamp 78 to glow very brightly, 115 as just described. If the subscriber vibrates his hook up and down, the lamp will pulsate accordingly.

The invention may be varied by those skilled in the art without departing from the spirit thereof. 120

What we claim, and desire to secure by Letters Patent is as follows:

1. In a telephone system the combination of a subscriber's station and a central station, a line annunciator, a switch, a circuit-breaker and means controlled by the subscriber and the said switch for connecting and disconnecting the annunciator to the said circuit-breaker to give different indica- 125 130

tions when a connection is desired and when the conversation is completed.

2. In a telephone system the combination of a subscriber's station and a central station, a line annunciator, a switch, a circuit-breaker for producing a pulsating current and means controlled by the subscriber and the said switch for causing the circuit-breaker to operate the annunciator when a connection is desired and for causing the said annunciator to operate when the conversation is completed.

3. In a telephone system the combination of a subscriber's station and a central station, a line annunciator, a source of current, a means for varying the said current and means controlled by the subscriber for directing the said current to the annunciator to indicate when the connection is desired and when the conversation is completed.

4. In a telephone system the combination of a subscriber's station and a central station, a line-annunciator lamp, means controlled by the subscriber and the operator for varying the light of the lamp.

5. In a telephone system the combination of a subscriber's station and a central station, a jack and a line annunciator associated with the said subscriber's line, a circuit-breaker and a plug-switch for connecting and disconnecting the said circuit-breaker with the said annunciator and a magnet controlled by the subscriber for causing the annunciator to give one indication when the connection is desired and to give a different indication when the conversation is completed.

6. In a telephone system the combination of a subscriber's station and a central station, a jack and a line-annunciator lamp associated with the said subscriber's line, a circuit-breaker, and means for normally connecting the said circuit-breaker with the said lamp and means controlled by the subscriber and the operator for causing the said lamp to give one indication when the connection is desired and an indication of a different character when the conversation is completed.

50 7. In a telephone system the combination of a plurality of subscribers' stations and a central station, a jack and an annunciator-lamp associated with each of the said subscribers' stations, a circuit-breaker normally connected with switches located in the said jacks, plugs adapted to operate the said switches, a means controlled by each subscriber and switch for causing the associated annunciator to give one indication when the connection is desired and a different indication when the conversation is completed.

65 8. In a telephone system the combination of a subscriber's station and a central station, a lamp located at the central station and controlled by the subscriber, a means

for causing the said lamp to give indications of different characters until the connections with another subscriber are made and the connections are broken.

9. In a telephone system the combination of a subscriber's station and a central station, an annunciator associated with the subscriber's line, plug-circuits located at the central station, means for causing the said annunciator to give an indication until the said plug-circuit is connected with the said subscriber's station and to cause a different indication until the said connection is broken.

10. In a telephone system the combination of a subscriber's station and a central station, a line-annunciator lamp, means located at the subscriber's station for controlling the said lamp and means located at the central station for controlling the said lamp, and means for causing the said lamp to produce lights of a different character when the subscriber desires to have a connection made and when the conversation is completed.

11. In a telephone system the combination of a subscriber's station and a central station, a line annunciator, means located at the subscriber's station for controlling the said lamp, means located at the central station for controlling the said lamp, and means for causing the said lamp to produce a light of one character when the means located at the subscriber's station is operated in one direction and for producing a light of another character when the means located at the subscriber's station is operated in another way.

12. In a telephone system the combination of a subscriber's station, and a central station, a line-annunciator lamp, means located at the subscriber's station and means located at the central station for controlling the said lamp, means for causing the said lamp to produce a fluctuating light when a connection is desired and for producing a steady light when the conversation is completed.

13. In a telephone central system the combination of a plurality of subscribers' stations, jacks associated with the said stations, an annunciator associated with each of the said jacks, means for causing the said annunciator to actuate in one way when the subscriber desires to be connected with another and in a second way when one subscriber thus connected to another desires to be disconnected and in a third way when the subscriber thus connected desires to be disconnected.

14. In a telephone central system the combination of a plurality of subscribers' stations, jacks associated with the said stations, an annunciator associated with each of the said jacks, means for causing the said annunciator to be actuated in one way when the subscriber desires to be connected with another and another way when either one of the

subscribers desires to be disconnected and in a third way when both subscribers desire to be disconnected.

15. In a telephone central system the combination of a plurality of subscribers' stations, jacks connected to the said stations, an annunciator associated with each of the said jacks, means for causing the said annunciator to be actuated when a subscriber desires to be connected with another and to be actuated in one way when a subscriber thus connected desires to be disconnected and to be actuated in another way when the other connected subscriber desires to be disconnected.

16. In a telephone central system the combination of a plurality of subscribers' stations, jacks connected with said stations, an annunciator associated with each of the said jacks, means for causing the said annunciator to be actuated when a subscriber desires to be connected with another and to be actuated in one way when one of the connected subscribers desires to be disconnected and in another way when the other of the connected subscribers desires to be disconnected and to be actuated when both subscribers desire to be disconnected.

17. In a telephone central system the combination of a plurality of subscribers' stations, jacks connected with said stations, an annunciator associated with each of the said jacks, means for causing the said annunciator to be actuated in one way when a subscriber desires to be connected with another and to be actuated in another way when one of the connected subscribers desires to be disconnected and to be actuated in a third way when the other of the connected subscribers desires to be disconnected and in a fourth way when both subscribers desire to be disconnected.

18. In a telephone central system the combination of an annunciator, switches for controlling the said annunciator, means for causing the said annunciator to be actuated in one way when one of two connected subscribers desires to be disconnected and to be actuated in another way when the other connected subscriber desires to be disconnected.

19. In a telephone central system the combination of an annunciator, switches for controlling said annunciator, means for causing the said annunciator to be actuated in one way when either one of two subscribers desires to be disconnected and to be actuated in another way when both subscribers desire to be disconnected.

20. In a telephone central system the combination of an annunciator, switches for controlling the said annunciator, means for causing the said annunciator to be actuated in one way when one of two connected subscribers desires to be disconnected and to be actuated in another way when the other con-

nected subscriber desires to be disconnected and to be actuated in a third way when both subscribers desire to be disconnected.

21. In a telephone central system the combination of a plurality of subscribers' stations, jacks connected with said stations, a lamp associated with each jack, means for causing the said lamp to give a light of one character when a subscriber desires to be connected with another subscriber and to give a light of another character when either subscriber desires to be disconnected.

22. In a telephone central system the combination of a plurality of subscribers' stations, jacks connected with said stations, a lamp associated with each jack, means for causing the said lamp to give a light of one character when a subscriber desires to be connected with another, to give a light of another character when one subscriber desires to be disconnected and to give a light of a third character when the other connected subscriber desires to be disconnected.

23. In a telephone central system the combination of a plurality of subscribers' stations, jacks connected with said stations, a lamp associated with each jack means for causing the said lamp to give a light of one character when one of two connected subscribers desires to be disconnected and to give a light of another character when the other of the connected subscribers desires to be disconnected and to give a light of a third character when both of the subscribers desire to be disconnected.

24. In a telephone central system the combination of a lamp, switches for controlling the said lamp, means for causing the said lamp to be actuated when either one of the subscribers desire to be disconnected and to give a light of a different character when both subscribers desire to be disconnected.

25. In a telephone central system the combination of a lamp, switches for controlling the said lamp, means for causing the said lamp to give a light of one character when one of two connected subscribers desires to be disconnected and to give a light of another character when another of the connected subscribers desires to be disconnected.

26. In a multiple-board central system the combination of a plurality of subscribers' stations, a plurality of jacks, connected to each station, a lamp associated with each set of jacks, means for causing the said lamp to be actuated when a subscriber desires to be connected with another and to be actuated when either subscriber desires to be disconnected.

27. In a multiple-board central system the combination of a plurality of subscribers' stations, a plurality of jacks connected to each station, an annunciator associated with each set of jacks, means for causing the said annunciator to be actuated when a subscriber

desires to be connected with another and to be actuated in one way when one subscriber desires to be disconnected and to be actuated in another way when the other subscriber desires to be disconnected.

28. In a telephone central system the combination of a plurality of subscribers' stations, jacks connected to the said subscribers' stations, means for connecting the said jacks together, an annunciator associated with each jack, means for causing the said annunciator to be operated in one way before its associated jack is connected to the

said connecting means and in another way after it is connected with the said connecting means and in a third way after the said connecting means is connected with another jack.

In testimony whereof we have signed our names to this specification in the presence of 20 two subscribing witnesses.
